UNITED STATES PATENT OFFICE

120,639

DESIGN FOR A COMBINED VEHICLE LAMP AND SUPPORTING BRACKET

Jack Galter, Chicago, Ill.

Application February 12, 1940, Serial No. 90,223

Term of patent 7 years

To all whom it may concern:

Be it known that I, Jack Galter, a citizen of the United States of America, residing at 711 West Lake Street, Chicago, Illinois, have invented a new, original, and ornamental Design for a Combined Vehicle Lamp and Supporting Bracket, of which the following is a specification, reference being had to the accompanying drawing, forming a part thereof.

Fig. 1 is a perspective view of a combined vehicle lamp and supporting bracket embodying my new design and showing the bracket in dotted lines; Fig. 2 is a top plan view; Fig. 3 is a bottom plan view; Fig. 4 is a front elevational view, and Fig. 5 is a rear elevational view of my combined vehicle lamp and supporting bracket.

The dominant features of my design reside in the portions represented in solid lines.

I claim:

The ornamental design for a combined vehicle lamp and supporting bracket, substantially as shown and described.

JACK GALTER.
